UNITED STATES PATENT OFFICE.

JAMES B. VAN ETEN, OF STROUDSBURG, PENNSYLVANIA.

COMBINED STOVE AND FIRELESS COOKER.

1,113,072.

Specification of Letters Patent.

Patented Oct. 6, 1914.

Application filed March 26, 1913. Serial No. 756,983.

To all whom it may concern:

Be it known that I, JAMES B. VAN ETEN, a citizen of the United States, residing at Stroudsburg, in the county of Monroe and 5 State of Pennsylvania, have invented new and useful Improvements in Combined Stoves and Fireless Cookers, of which the following is a specification.

The invention relates to stoves, and more 10 particularly to the class of combined stoves and fireless cookers.

The primary object of the invention is the provision of a stove wherein a fireless cooker is built therewith, the latter being 15 a part of the said stove so that it will be in a convenient position for use to receive food after having been heated by the stove.

Another object of the invention is the provision of a stove of this character either 20 of the gas or coal type, wherein the heat from the stove can be utilized for heating a unit which forms a part of a fireless cooker, whereby the latter can be used in the ordinary well-known manner and is a part 25 of the stove.

A further object of the invention is the provision of a stove of this character wherein food may be cooked either upon the stove or in a fireless cooker forming a part 30 of the said stove, thereby obviating the necessity of maintaining a fire within the stove for an extended period of time.

A further object of the invention is the provision of a stove of this character which 35 is simple in construction, compact, thoroughly reliable and efficient in its purpose, and inexpensive in manufacture.

With these and other objects in view the invention consists in the construction, combination and arrangement of parts as will 40 be hereinafter more fully described, illustrated in the accompanying drawing, and pointed out in the claim hereunto appended.

In the drawings:—Figure 1 is a fragmentary vertical longitudinal sectional view of a stove embodying the device. Fig. 2 is a horizontal sectional view through the stove. Fig. 3 is a vertical transverse sectional view 45 through the cooker.

Similar reference characters indicate cor-

responding parts throughout the several views in the drawing.

Referring to the drawings by numerals, 5 designates generally a stove which may be either of the gas or coal type and includes 55 a fire box and oven, as usual.

Forming a part of the stove 5 is a fireless cooker comprising a body 9 which is attached to or integrally formed with the body of the stove 5, and into this body 9 is 60 projected a heating unit 10 which is secured to the stove body. Formed in the body 9 of the fireless cooker are the usual pockets or cells 11 adapted to receive receptacles containing food to be cooked, the said 65 pockets or cells 11 being closed at their tops by means of removable lids 12, while partially surrounding the said pockets or cells 11 is a packing 13 made of suitable heat or cold non-conducting material. 70

Disposed between the wall adjacent to the fireless cooker body 9 and the wall of the oven is a partition 14 which is arranged in the stove draft flue 8, and this partition is formed with an opening 15 which is adapted 75 to be closed by a hinged damper 16, the latter being provided with a suitable handle 17 whereby it may be manipulated for the opening and closing of the damper, the opening 15 in the partition 14 permitting 80 heat circulating through the flue 8 to pass into the zone of the unit 10, whereby the latter will become heated so that food placed within the fireless cooker may be cooked by the heat radiating from the unit 10. 85

In Fig. 3 there is shown a slight modification of the invention, wherein the pockets 18 have removably fitted therein heating units 19 which are adapted to be extracted from the pockets and placed upon the stove 90 for the heating thereof. After the units 19 have been heated on the stove the same are replaced within the pockets 18 for the cooking of food when deposited therein.

It is of course to be understood that the stove may be of any well-known type and that the fireless cooker is formed therewith to be a part of the same.

From the foregoing it is thought that the construction and manner of operation of 10

the device will be clearly understood, and therefore a more extended explanation has been omitted.

What is claimed is:—

- 5 The combination with a stove having an opening in one wall, of a fireless cooker body mounted on the stove at one side thereof and having a pocket coinciding with the opening in the wall of the stove for

communication therewith, and a heating unit fitted within the opening and extended within the pocket.

In testimony whereof I affix my signature in presence of two witnesses.

JAMES B. VAN ETEN.
